UNITED STATES PATENT OFFICE.

GEORGE W. CASWELL AND CHARLES E. WELT, OF CLIFFONDALE, MASSACHUSETTS.

COMBINED LEVEL AND PLUMB.

1,169,005.

Specification of Letters Patent. Patented Jan. 18, 1916.

Application filed September 15, 1915. Serial No. 50,862.

To all whom it may concern:

Be it known that we, GEORGE W. CASWELL and CHARLES E. WELT, citizens of the United States, residing at Cliffondale, Saugus, in the county of Essex and State of Massachusetts, have invented new and useful Improvements in Combined Levels and Plumbs, of which the following is a specification.

10 This invention relates to a combined level and plumb.

The primary object of the invention is to provide a device of this class with an especially constructed dry battery wherein the 15 center carbon electrode is projected beyond the opposite ends of the body, each of said electrodes having a bulb arranged thereon, a contact plate being arranged upon the body at the zinc of the battery electrode, 20 contact members being arranged above the plate and adapted to be forced into contact with the said plate by the pressure of suitable push buttons arranged for such purpose.

25 With the above and other objects in view, the improvement resides in the construction, combination and arrangement of parts set forth in the following specification and falling within the scope of the appended 30 claims.

In the drawings: Figure 1 is a side elevation of a level and plumb provided with our improvement, Fig. 2 is a top plan view of the same, Fig. 3 is a transverse sectional view approximately on the line 3—3 of Fig. 1, Fig. 4 is a detail side elevation with the side plate for the battery box removed, Fig. 5 is a central longitudinal sectional view approximately on the line 5—5 of Fig. 2, Fig. 40 6 is a perspective view of the battery, Fig. 7 is a similar view of one of the bulbs with the reflector thereon.

The device comprises the usual stock 1, the same having arranged in suitable cavities or side openings provided therefor the level glass bubble-containing bulb 2 and the plumb bubble-containing bulb or tube 3, the bubbles of each of the bulbs being perceptible through openings provided in suitable 50 covering plates 4 and 5 respectively, and the glass bulbs may be adjusted or regulated in any desired or preferred manner so as to center the bubbles therein. The stock 1 is approximately centrally provided with a 55 substantially rectangular opening which communicates with one of its sides and

within the said opening is arranged a metallic box or casing 6, the same preferably having its outer sides flanged and formed with threaded openings, whereby a closure plate 60 7 may be removably connected with the said box or casing 6.

The box 6 is adapted to receive a removable metal battery box, indicated by the numeral 8, and this box, in the showing of 65 the drawings, comprises two sections 9 and 9' respectively, each of said sections being connected to the inner face of the box through the medium of removable elements such as screws 10. The box 8 is arranged 70 centrally of the plumb 3 and said box is adapted to receive a removable battery 11, the same being of an especial construction, the said battery comprising an outer body portion 12 which may be of any desired size 75 and length, and the center carbon electrode 13 projects through both of the ends of the body 12.

The numeral 14 designates a contact plate which is arranged upon the body and which 80 communicates with the zinc of the battery electrode, and the projecting ends of the carbon electrode have connected thereto lamps 15 and 16 respectively, the lamp 16 being disposed centrally or directly opposite the 85 bubble in the bulb 2, while the lamp 16 is likewise disposed to the rear centrally of the bubble in the bulb 3. The contact plate 14 is arranged between the sections 9—9' of the 90 battery box 8, and connected with each of the said sections are spring contact members 17 and 18 respectively.

The stock 1 is provided with a pair of push buttons 19 and 20 respectively, each of the said push buttons including a flanged portion 21 which is arranged within an annular depression 22 provided in a sleeve or casing 23, and the said flanges are contacted by springs 24 which surround the buttons 19 and 20, forcing the buttons in an outward 100 direction from the spring contacts 17 and 18, but not beyond the surface of the stock. Each of the lamps 15 and 16 is provided with a dished or cup-shaped reflector 25 and 26 respectively, and it is, of course, to be understood that the stock is provided with 105 suitable cavities or depressions to receive the bulbs of the lamps 15 and 16 as well as the reflectors 25 and 26 so that the rays of the lamps may be directed to the glass bulbs 2 and 3. With a battery constructed in accordance with the present invention, it will 110

be apparent that either of the spring contact members 17 or 18 is forced into engagement with the contact plate 14 of the battery, either of the lamps 15 or 16 may be illuminated, and further that should both of the push buttons 19 and 20 be operated at the same time to bring the contact springs 17 and 18 into engagement with the contact plate 14, both of the lamps 15 and 16 will be 10 simultaneously illuminated.

Having thus described the invention, what we claim is:

1. In a device of the class described, the combination of a supporting stock having 15 sight openings therein and bulb tubes arranged one in each of the sight openings and visible from the exterior of the stock, a lamp adjacent each of the bulbs, a single battery for both of the lamps, said battery including 20 a body having its center carbon electrode projecting beyond the ends and connected with the lamps, a contact plate communicating with the zinc of the battery electrode, spring contact members arranged adjacent 25 the contact plate, and a push button for each of the said contact springs.

2. In a device of the class described, the combination of a supporting stock having

bubble tubes therein visible from the exterior of the stock, said stock having a central 30 receptacle, a box within the receptacle, a closure to one side of the stock for the box, a battery box removably secured in the first named box, said battery box comprising two sections, a longitudinally arranged battery 35 removably secured in the battery box, said battery comprising an outer zinc casing, a carbon electrode which is surrounded by the zinc casing and which extends centrally of the casing and projects through the opposite 40 ends thereof, a contact plate upon the casing, a contact spring carried by each of the sections of the battery box and disposed above the contact plate, a push button for each of the springs, a lamp connected with each of the ends of the center carbon or electrode, a reflector for each of the lamps, and each of said lamps being disposed adjacent one of the bubble tubes.

In testimony whereof we affix our signatures in presence of two witnesses.

GEORGE W. CASWELL.
CHARLES E. WELT.
